UNITED STATES PATENT OFFICE

2,630,788

VALVE OPERATING MECHANISM FOR CONTROLLING THE STEAM EVENTS IN STEAM ENGINES

Herman G. Mueller, Erie, Pa., assignor, by mesne assignments, to Skinner Engine Co., Pittsburgh, Pa., a corporation of Pennsylvania

Original application February 21, 1947, Serial No. 730,114. Divided and this application May 12, 1948, Serial No. 28,612

3 Claims. (Cl. 121—102)

1

This invention relates generally to novel valve operating mechanism for a multi-cylinder steam engine and it relates more particularly to a valve operating mechanism for steeple-compound, poppet valve, reversing stationary and marine engines. This application is a division of my application Serial Number 730,114, filed February 21, 1947, which matured as Patent No. 2,572,652, issued October 23, 1951.

Most of the compound, triple and quadruple expansion marine steam engines in service utilize slide valves with a few of the more modern steam engines having poppet valves. The valve operating mechanism in present steam engine practice is entirely unsatisfactory and inefficient and it is not adaptable for conversion of old type valve operating mechanism to valve operating mechanism for modern steam engines utilizing the existing conventional Stephenson linkage valve gear and the existing reversing jack and controls.

It is, accordingly, an object of my invention to provide a novel valve operating mechanism for a steam engine and it is more particularly an object of my invention to provide a valve operating mechanism for a steeple-compound, steam engine which is simple in construction, economical in cost, economical in manufacture and efficient in operation.

Another object of my invention is to provide a novel poppet valve mechanism for a steam engine with a variable cut-off and other steam events, desirable for maximum economy and with proper maneuverability.

Another object of my invention is to provide a compound multi-cylinder steam engine valve operating mechanism which may be adapted for use with any number of cranks and in which a complete steam cycle is carried through on each crank.

Another object of my invention is to provide novel valve operating mechanism for multi-steeple compound cylinders with piston and cylinder heads and poppet valves and inlet and exhaust manifolds which may be adapted to and mounted on conventional open frames or columns now in use, and which will utilize the existing cranks, connecting rods, cross heads, bedplate with main bearings and shafting and the conventional eccentric valve gearing, reversing

2

mechanisms, etc. already assembled and in use on existing engines.

Another object of my invention is to provide novel multi-steeple compound steam cylinders with a poppet valve gear which can be actuated from existing conventional eccentrics and reversing mechanisms.

Other objects of my invention will become evident from the following detailed description, taken in conjunction with the accompanying drawings, in which:

Fig. 1 is a side elevational view partly in vertical section of my novel valve actuating mechanism controlling and operating the low pressure valve in a cylinder head between a high and low pressure cylinder of a steeple compound steam engine;

Fig. 2 is a horizontal sectional view taken through the cylinder head 10 in Fig. 1;

Fig. 3 is a side elevational view with fragments thereof broken away showing my novel valve operating mechanism controlling the admission valve and an exhaust valve for exhausting steam from the low pressure cylinder;

Fig. 4 is an enlarged fragmentary side elevational view showing my novel valve operating mechanism;

Fig. 5 is a fragmentary view taken on the line 11—11 of Fig. 2; and

Fig. 6 is a fragmentary view showing the packing box engaging the piston rod disposed between the high pressure cylinder and the low pressure cylinder of my novel steam engine.

For the purposes of illustration, I have shown my novel steam cylinders, cylinder heads, and valve operating mechanisms mounted on conventional marine triple expansion engine columns, although it will be evident that my novel cylinders, cylinder heads, manifolds, and valve operating mechanisms may be mounted on any type of conventional frame or column with any number of cranks.

Referring now to the drawings, Figs. 1 to 6 inclusive show a low pressure cylinder 4 mounted on columns 2, a high pressure cylinder 5 being disposed in vertical alignment above the low pressure cylinder 4. The high and low pressure cylinders 5 and 4, respectively, have a piston rod 12 extending axially thereof and through a cylinder head 10 between the high and low pressure

cylinders 5 and 4. The piston rod 12 has a piston 13 fixed thereon movable in the high pressure cylinder 5 and it also has a piston 15 fixed thereon movable in the low pressure cylinder 4. The complete description of the cylinders, pistons, and other elements and parts of the steam engine in which my valve operating mechanism is shown is fully set forth and described in my Patent No. 2,572,652, issued October 23, 1951.

An open passage 44 in the cylinder head 10 leads directly to the upper end of the low pressure cylinder 4 from the high pressure cylinder 5. Steam passes freely from the high pressure cylinder 5 to the top of the low pressure cylinder 4 and vice versa. A high pressure steam line 45, connected with a manifold, is secured to the top surface of the cylinder head 10 diametrically opposite to the steam line 43 and connects with a steam chamber 46, the steam thereby passing from the chamber 46 upon the opening of the poppet valve 47 into the port 47a, which is open to the high pressure cylinder 5. Exhaust from the high pressure cylinder 5 is continued after the pistons 13 and 15 in the high pressure and low pressure cylinders 5 and 4, respectively, recede from the top of their stroke by opening poppet valve 48 which connects the port chamber 47a, open to the high pressure cylinder 5, with a steam passage 50 leading to the upper end of low pressure cylinder 4. Poppet valve 52 is provided in the cylinder head 10 to exhaust steam on the upstroke of the low pressure cylinder 4 to a steam chamber 53 which passes the exhaust steam outwardly through passage 54 and exhaust line 55 to a condenser (not shown).

In controlling the steam events in a steam engine, I may utilize existing conventional eccentrics on a conventional vertical marine triple expansion engine as I have shown in the drawings; however, my novel valve actuating mechanism may be operated by any other suitable means. In Fig. 1, I show conventional links 62 operated by eccentrics and eccentric rods (not shown) connected to valve rod 63, pivoted rocker arm 64, and adjustable link rod 65. The eccentric motion may be carried by any suitable linkage system connected to an adjustable link rod 65. In other words, any suitable system may be utilized for operating the adjustable link rod 65 without departing from my invention.

The valve rod 65 is pivotally connected to a double-armed rocker 66, which is adjustably mounted on a transversely extending camshaft 67, passing into camboxes 120 and 120a mounted on low pressure cylinder 4 on both sides of rocker 66. Each end of the camshaft 67 oscillates in flanged supporting bearings 121 bolted to the outer faces of camboxes 120 and 120a. The rocker 66 carries two circular faces 122 concentric with shaft 67, and are adjustably bolted to flanges 123 and 123a of sleeves 124 and 124a disposed about the camshaft 67, and which extend into camboxes 120 and 120a through packing glands 125.

To the end of sleeve 124a, within cambox 120a, is bolted cam hub 68 concentric with and adjustably on camshaft 67, and has disposed thereon a removable cam member 69 with a key portion 70, which engages a slotted portion 71 in the side of the cam hub 68, and which is secured by screw bolt 72. A cam roller 73, mounted on the lower end of rocker arm 74 pivoted on shaft 75a, engages the cam member 69, while the upper end 76 of rocker arm 74 engages, by means of tappet screw 77 secured by nuts 77a, the valve

stem 78 of poppet-valve 47 to reciprocate and open and close this valve mounted in the flanged cage 79.

To the end of sleeve 124, within the cambox 120 (Fig. 4), is bolted a similar cam hub 81 concentric with and adjustable on camshaft 67, and has secured thereon by screw bolts 85 a cam member 82 having a key portion 84 in the side of cam hub 81. The rocker 86 is pivoted on shaft 75 and carries a cam roller 87 at its lower end, engaging the cam member 82. The upper end 88 of the rocker arm 86 engages, by means of tappet screw 88a and secured by nut 88b, valve stem 89 of the large exhaust poppet-valve 48, and reciprocates and opens and closes it in the flanged cage 91 in which it is supported.

It should be noted here that the cam member 69, in cambox 120a, has its hump on the upper end, whereas cam member 82 in cambox 120 has its hump on the lower end. Thus, with reciprocation of valve rod 65 upwardly, cam member 82 in cambox 120 will engage roller 87 of rocker 86, on whose upper end tappet screw 88a will engage valve stem 89, opening valve 48. With reciprocation of valve rod 65 downwardly, valve 48 will be closed, and the hump on cam member 69 will engage roller 73 in cambox 120a on rocker 74, and tappet screw 77 will engage valve stem 78, opening valve 47.

The timing and amount of these openings is dependent upon the detailed design of the cam members 69 and 82, the lever ratios of the rocker arms 74 and 86, and the adjustment by means of the flanges on sleeves 124 and 124a with respect to the faces 122 on rocker 66.

In cambox 120a is movably mounted on shaft 75a a second rocker arm 94 (Figs. 10 and 11) which carries an inwardly extending abutting member 93, which is engaged by a complementary abutting member 92 on rocker arm 74. The upper end of rocker arm 94 engages, by means of tappet screw 95 secured by nut 95a, a valve stem 96 of poppet valve 52 mounted in flanged cage 52a.

Thus, whenever cam roller 73 is lifted by the hump on cam member 69, both poppet valves 47 and 52 will be opened, the former serving to admit steam under the high-pressure piston 13 on the upstroke and the latter to exhaust steam from the low-pressure cylinder 5 above the low-pressure piston 15, which will also be on its upstroke. The lift on exhaust valve 52 will be less than that on admission valve 47, due to the short lever arm on rocker 94 as compared with the long lever arm on rocker 74.

This construction is used so that exhaust valve 52 may be manually lifted independent of admission valve 47 for the purpose of venting the low-pressure cylinder 5 continuously to the condenser for easy starting. This is accomplished by a sliding rod 99 mounted in sleeve 130, which is screwed at its lower end into cap plate 131 bolted to the underside of cambox 120a. To the bottom of cap plate 131 is bolted a small cylinder 133, in which is slidably contained a close-fitting piston 132. All of the cylinders 133 are connected by a steam line 134 screwed into the bottom of each cylinder 133, and which leads to a hand-operated valve mounted near the main controls, and which is supplied with high-pressure steam.

Thus, when the operator wishes to start the engine up slowly in either direction after he has positioned the valve gear for the direction of rotation desired, he admits steam under pressure under all pistons 132, which then are forced to

the top of cylinder 133, engaging slide rod 99 which in turn engages rocker arm 94 and lifts valve 52, thereby venting all the low-pressure cylinders to the condenser. This, as will be seen, is accomplished without disturbing the operation of the admission valve 47 which is always operated by the cam member 69. Immediately after the engine starts, the operator shuts off the steam pressure under the pistons 132, and the steam under these pistons will leak out and the piston will drop, disengaging slide rod 99 from rocker arm 94 and valve 52. The rocker arm 94 and valve 52 then return to their normal function of exhausting the low-pressure cylinder 4 on the up-stroke of piston 15 only, and by means of cam member 69 as described above.

By proper disposition of the cam hubs and cam members 68, 69, 81 and 82, by means of coupling flanges 123 and 123a, and by proper proportioning of rockers 66 with the movement of the eccentric valve gear, proper steam events in the high and low-pressure cylinders 5 and 4 may be obtained. Furthermore, any system of eccentrics or any other type of conventional reciprocating valve gear may be adapted for use with my novel valve mechanism, although I have only shown the adaption to the use of the conventional Stephenson eccentrics and links of a conventional triple-expansion steam engine with my novel valve mechanism. All valves and the mechanisms therefor are independently adjustable, therefore providing for maximum efficiency.

In operation, high-pressure steam passes through steam lines 45 to the steam chamber 46 in cylinder head 10 and from thence through the poppet-valve 47 to the high-pressure cylinder 5. This high-pressure steam acts upwardly on the underside of piston 13 in the high-pressure cylinder 5, and the steam is cut off at any suitable predetermined point by proper adjustment of the cam hub 68 and cam member 69 controlling the poppet-valve 47. When the piston 13 passes above exhaust ports (not shown) in the side wall of the upper end of the high pressure cylinder 5, steam passes outwardly between the inner sleeve 35 and the outer wall 37 and equalizes the pressure in the high-pressure cylinder with the pressure on top of the high-pressure piston 13 and in the annular space between sleeve 35 and outer wall 37 and through steam line 43 and passage 44 and with the steam on top of low-pressure piston 15. Immediately after starting the downward stroke, the exhaust ports in the upper end of the high pressure cylinder 5 are again closed by piston 13, but by this time the exhaust poppet-valve 48 is open, thereby continuing the exhaust from the high-pressure cylinder 5 through this valve into the low-pressure cylinder 4. This cylinder is permanently open through passages 44, steam line 43, and the annular space between liner 35 and outer wall 37 to the top of the high-pressure piston 13. Both high-pressure piston 13 and low-pressure piston 15 then continue the downward stroke, and when they have reached a predetermined portion of their stroke, the exhaust poppet-valve 48 is closed. The piston 15 in the low-pressure cylinder 4, as it approaches the bottom of the stroke, opens exhaust ports (not shown) in the side wall of the low pressure cylinder 4 intermediate the ends thereof and exhausts all of the steam, both in low-pressure cylinder 4 and on top of high-pressure piston 13 in high-pressure cylinder 5, to an exhaust line. Thus it is apparent that the top of piston 13 in high-pressure cylinder 5 serves to give an addi-

tional low-pressure displacement complementing that of the main low-pressure piston 15. The low-pressure piston 15, after reaching the bottom of its stroke, begins its upward stroke, and at a predetermined point in this upward movement, the low-pressure exhaust valve 52 is opened, continuing the exhaust to the condenser through exhaust lines 55 and 56. It will be evident upon inspection that proper movements and control of the poppet-valves 47, 48 and 52 may be obtained by proper design of the cam members 69 and 82 and proper positioning relative to the rocker arm 66. The cam members 69 and 82 are removable and can be altered by filing, when necessary, for perfect adjustment of all the poppet-valves 47, 48 and 52. After the desired indicator cards are obtained, the cam members 69 and 82 are hardened and permanently returned to their final positions on cam hubs 68 and 81.

The steam events in my novel steam cylinders are properly taken care of by the novel valve and cam arrangements which I have provided, and which may be adapted for use with any conventional bedplate and columns now in use with conventional eccentrics or any other type of conventional reciprocating valve gear. My novel cylinder head and valve gear mechanism give accurate steam control throughout the entire range of ahead and astern cutoff adjustments, provides ample port areas, automatic pressure release, and it permits the efficient use in a steam engine of high-pressure and high-temperature steam used in modern steam practice.

Various changes may be made in the specific embodiment of my invention, without departing from the spirit thereof, or from the scope of the appended claims.

What I claim is:

1. A valve operating mechanism for a multiple cylinder steam engine having an admission valve for the admission of high pressure steam to the high pressure cylinder, an exhaust valve for exhausting steam from the high pressure cylinder to the low pressure cylinder, and an auxiliary valve for exhausting steam from the low pressure cylinder comprising pivoted rockers having one end thereof connected to said admission and exhaust valves for actuating same, an auxiliary pivoted rocker adjacent said rocker connected to said admission valve having one end thereof connected to said auxiliary valve for actuating same, laterally extending, complementary abutting members on said rocker actuating said admission valve and said rocker actuating said auxiliary valve whereby said abutting members engage each other and actuate said auxiliary valve rocker upon a predetermined rotational movement of said admission valve rocker, a cam shaft, cam members on said cam shaft, cam rollers carried by said rockers connected to said admission valve and said exhaust valve engaging the cam members on said cam shaft, and motion transferring members for oscillating said cam shaft.

2. A valve operating mechanism as set forth in claim 1 wherein said cam members are independently adjustable and removable.

3. A valve operating mechanism as set forth in claim 1 wherein means are connected to said auxiliary valve for selectively actuating said auxiliary valve independent of said abutting means heretofore mentioned comprising a rod connected to said auxiliary rocker, a piston for actuating said rod, a cylinder in which said piston reciprocates, a source of steam for said cylinder, and means for

controlling the admission of steam to said cylinder.
